DESCRIPTION

FIG. 1 is an exploded perspective view of an animal lure showing our new design;

FIG. 2 is a front elevational view thereof;

FIG. 3 is a rear elevational view thereof with the hanger folded down;

FIG. 4 is a side elevational view thereof;

FIG. 5 is a side elevational view thereof;

FIG. 6 is a top plan view thereof; and,

FIG. 7 is a bottom view thereof.

The broken lines are for purposes of illustration only and form no part of the claimed design.

FIG. 1

FIG. 4

FIG. 5

FIG. 2

FIG. 3

FIG. 6

FIG. 7
